UNITED STATES PATENT OFFICE.

EDGAR KINSMAN, OF MALAGA, NEW JERSEY, ASSIGNOR OF ONE-HALF TO
ALFRED B. RICHMAN, OF SAME PLACE:

PRINTING-TELEGRAPH.

SPECIFICATION forming part of Letters Patent No. 664,761, dated December 25, 1900.

Application filed December 21, 1899. Serial No. 741,177. (No model.)

To all whom it may concern:

Be it known that I, EDGAR KINSMAN, a citizen of the United States, residing at Malaga, in the county of Gloucester and State of New Jersey, have invented new and useful Improvements in Printing-Telegraphs, of which the following is a specification.

My invention relates to printing-telegraph instruments; and the objects of the same are 10 to reduce the number of type-keys to the minimum, while the maximum number of printing characters or types are retained; to provide a system of switch-keys which may be quickly operated to shift the type-plate 15 into position to print different sets or rows of characters when the type-keys are actuated; to provide an automatic spacing-roller which carries the paper in a spiral line of such pitch that one revolution of the roller moves the 20 paper just the distance required for the space between the lines of print, provision being made for automatically feeding the paper the required distance for each letter as it is printed; to provide means for moving the 25 full set of types in four directions automatically to bring the desired type to its proper position for printing at the stroke of its key, and to provide a combined mechanical and electrical synchronizing system whereby mes- 30 sages are printed simultaneously at both ends of the line.

By my system of type-keys and switch-keys a greater speed in operation is attained, as but twelve type-keys are used and four 35 switch or shift keys, and these may be quickly manipulated, as they are practically in one row or line in front of the instrument. When this simple arrangement of keys is thoroughly understood by the operator, a 40 speed of eight letters per second may be accomplished, and since the paper-roller is automatic in its operation no time is lost in spacing. An entire page of the message may be printed without concern on the part of the 45 operator, excepting the manipulation of the keys. When this page has been removed from the paper-roller, another may be transmitted and printed, and so on, it being necessary only to shift the paper-carriage once 50 for each page printed, the length and width

of the page depending upon the length and diameter of the paper-roller.

Many other advantages arising from the simplicity in construction and arrangement of parts will hereinafter more fully appear in 55 the detailed description of my invention.

In the accompanying drawings, which form part of this specification, I have illustrated an instrument involving the principle of my invention; but I do not desire to have it understood that the details of structure are to be adhered to, as many changes may be resorted to which will fairly fall within the spirit and scope of my invention.

Figure 1, Sheet 1, is an elevation of an instrument made in accordance with my invention. Fig. 2, Sheet 2, is a plan view of the same. Fig. 3, Sheet 3, is a vertical sectional view of the instrument on the section-line 1 1, Fig. 1, looking toward the left. Fig. 4, 70 Sheet 4, is a view, partially in section and partially in elevation, of the paper-roller, the ink-ribbon, the type-plate, the cam-wheel for operating said type-plate, the type-lever, the commutators, and contiguous parts, some of 75 the parts being broken away to better illustrate the construction of the other parts. Fig. 5, Sheet 5, is a plan view of the paper-roller and the superposed type-plate and adjacent parts, said view being taken on line 80 5 5, Fig. 1. Fig. 6, Sheet 5, is a section on the line 6 6, Fig. 1, of the magnets for shifting the type-plate. Fig. 7, Sheet 5, is a vertical sectional view of the type-plate, the cylinder mounted within said type-plate, the guide- 85 ways, and the cam-wheel, a segment of the latter being shown in dotted lines. Fig. 8, Sheet 5, is a detail perspective view of the type-plate, the type being removed therefrom. Fig. 9, Sheet 5, is a detail perspective view 90 of the cylinder for the type-plate. Fig. 10, Sheet 5, is a detail perspective view of one of the type and its retracting-spring. Fig. 11, Sheet 6, is an end elevation of the paper- 95 roller, showing the ratchet-and-pawl mechanism for controlling the intermittent movement of said roller. Fig. 12, Sheet 6, is a broken central longitudinal section through the paper-roller, its worm-shaft, and actuating-gears. Fig. 12^a is a perspective view of 100

the spacing mechanism with parts broken away. Fig. 13 is a development of the cam-wheel. Fig. 13^a is a development of the commutator-rings and, considered in connection with Fig. 13, shows the correspondence of the lugs and straight portions of the grooves in the cam-wheel. Fig. 14 is an elevation of one of the commutator-rings, together with the brushes. Fig. 14^a is a view of another one of the commutator-rings, together with the guide-brush bearing on a lug. Fig. 15 is a detailed section showing the brake-lever for the worm-shaft. Fig. 16 is a diagrammatic view of the electrical connections of the printing-keys, synchronizing-circuit, bell, motor, spacing mechanism, and printing mechanism at both stations. Fig. 17 is a diagrammatic view of the shift mechanism and the electrical connections pertaining thereto for both stations.

Like characters of reference designate like parts wherever they occur in the different views of the drawings.

It will be understood that my instrument is a combined transmitter and receiver—that is to say, an instrument being located at opposite ends of the line or at intermediate stations may be operated to send or receive messages, and when used as a receiver the operator is only required to make slight changes in the electrical connections to remove the pages as fast as they are printed and to keep the paper-roller supplied.

The keyboard has mounted thereon two series of keys, one series of type or printing keys 5 and the other series of shifting-keys 6 for moving the type-plate transversely. The type-keys 5 may be arranged in a single line across the front of the support or base 1, there being twelve so-called "type-keys." Slightly in the rear of the type-key buttons and in the center of the series four switch-keys 6 are arranged. These keys may be of any suitable construction, and, as shown, each consists of a button secured to the outer end of a bar 7, the inner end of said bar being attached to a spring 8, secured to a block 9, rising from the support 1 by screws 9^a, provided with means for attaching wires. A tension-screw 10 passes through the bar 7 and is designed to adjust the limits of vibration of the keys. The contact-points 11 for the type-keys pass through the support 1 and are connected inside the cabinet to an armature 12, suspended above the magnets 3. Contact-points 12^a are also provided, to which the upper ends of the magnet-wires are attached. These contact-points are located under the armature, so that a circuit is completed through them and the key whenever one of the keys 5 is depressed.

The four switch-keys 6 are supported in the same manner as the type-keys. The two middle keys are provided each with a contact-point 6^a, insulated from the body of the key. These points are adapted to fit between the two pieces 6^b when the key is in its up-

per or normal position, thereby completing the circuit through these points. All four of keys 6 are each provided with a key-magnet 7^a 4, located in the cabinet under an armature 13, suspended from the keys. Contact-points 13^a are placed beneath the armature, and the upper ends of the magnet-wires are attached thereto, so that a circuit may be completed 75 through the key when it is depressed. The keys are thus held down by the magnets until the circuit is broken, as hereinafter described.

Referring now to Figs. 7, 8, 9, and 10, the type-plate 14 consists of a plate having four rows of perforations and twelve perforations in each row. In each one of these perforations a type 15 is mounted to move endwise. These types are constructed as shown in Fig. 85 10 and consist of a round shank 16, which is screw-threaded at one end to accommodate the cap 17. The type-face is formed on the opposite end of the shank 16, and a spring 18 surrounds the shank and bears at one end 90 against the cap 17 and at the other end against the inner surface of the type-plate 14. The cap 17 may be adjusted to regulate the impression of the type upon the paper. The arrangement of types in the perforations in 95 the type-plate is as follows:

1	2	3	4	5	6	7	8	9	0	1	%
A	B	-	O	D	W	Y	B	C	D	F	G
H	J	M	L	N	Z	P	O	R	S	T	V
X	Z	-	N	.	..						

Flanges 19 extend downward from the type-plate, and projecting from the upper side of 105 said plate are segmental sections 20 of a cylinder which may be called the "type-cylinder." Guide-ribs 21, formed on the segmental sections 20, are fitted to slide in a guide-frame 22, having guide-grooves 23. Fitted within 110 the segmental sections 20 of the type-plate 14 is a traveler-support 34, Fig. 9, consisting of the segments 35 and the flanged top plate 36. Journaled in an aperture in the top plate 36 is a traveler-wheel 37, and in line therewith 115 on said plate is a guide-lug 38. The wheel 37 and the guide-lug 38 are designed to travel in the grooves 39 of a cam-wheel 31 to impart a longitudinal movement to the type-plate, thus enabling any letter in the type-plate to 120 be brought into position for printing.

Referring now to Fig. 4, it will be seen that the guide-frame 22 is suspended upon rods 24 24^a, connected to the end cross-bars 25 of the guide-frame. These rods 24 24^a are provided with collars 26, loosely fitted to the shaft 27. The collar 26 on the rod 24^a is provided with upwardly-extending rods 28.

Referring now to Fig. 6, which shows the shifting mechanism, the numeral 47 designates the top cross-bar of the frame, and secured to said cross-bar is a block 47^a, which serves as a support for a metal yoke 47^b. Secured to the ends of the depending arms

of this yoke are straps 47^c, Fig. 2, which are attached by screws to the magnets 30³ and 30⁴. These four magnets are arranged oppositely and in pairs and are rigidly connected 5 to the yoke 47^b. Depending from the block 47^a are metal straps 47^a, to the lower ends of which are pivoted the pendent arms 30^b. These arms extend downward between the pairs of magnets 30³ and 30⁴ and are attached 10 to the intermediate blocks 30^c. A cross-brace 30^d connects the pendent arms 30^b and causes said arms to operate in unison. Connected to the block 47^a are the depending strap-springs 30^e, the lower ends of which 15 springs bear against the outer surfaces of blocks 30^c and serve to return the magnets 30³ and 30⁴ to their original positions after each movement thereof. These magnets 30³ and 30⁴ are also arranged oppositely and in 20 pairs beneath the magnets 30³ and 30⁴, being rigidly tied in pairs by the blocks 30^c. Rigidly attached to the upper ends of rods 28 is 25 a strap 29, carrying an armature 29^a, Fig. 4, which extends horizontally between the magnets 30³ and 30⁴ and is normally out of contact with said magnets. A vertical strap 29^b connects the armature 29^a with an armature 29^c for the upper pairs of magnets 30³ and 30⁴. The distance between the lower magnets 30³ and 30⁴ is such that when the armature is attracted to one or the other of these 30 pairs of magnets the type-plate is swung transversely by rods 28 and 24^a and one of the intermediate lines of type brought into 35 printing position. The springs 30^e are of sufficient stiffness to hold the magnets 30³ and 30⁴ in position during this operation. The distance between the upper pairs of magnets 30³ and 30⁴ is such that when the 40 armature 29^c is attracted thereby the type-plate is swung just far enough in either direction to bring the outer lines in printing position. The lower magnets 30³ and 30⁴ do not interfere with the operation just described, because they depend from arms 30^b and will swing backward when armature 29^a comes in contact therewith, the springs 30^e returning them to their initial positions after each oscillation. The electrical operation 45 of this mechanism, which is controlled by the switch-keys 6, will be hereinafter described.

The cam-wheel 31, Fig. 13, is keyed to the main driving-shaft 27, and its periphery is 50 provided with grooves 39. These grooves are practically continuous or, in other words, are formed as a connected groove passing around the wheel to provide a guideway to shift the type-plate longitudinally thereof. These 55 grooves consist of a combination of straight, curved, and diagonal portions. The straight portions (designated by the characters 39^a to 39^f, serially and inclusive) correspond to the commutator-rings 40, of which there are twelve 60 in number. The lugs 45 on said rings are set to correspond with these straight portions of the grooves 39 of the cam-wheel. It will be

noted that there is but a single straight portion 39^a and 39^f, while the other straight portions occur in pairs. For this reason the first and 70 the last of the commutator-rings are provided with but one lug each, while each of the other rings has two. These commutator-rings 40 are secured together with intervening rings of insulating material 43, and the whole commutator 40 is secured to the hub of the cam-wheel 31 by screws 41, as shown in Fig. 4. These rings 40 are each provided with a slot or division 44, which is used as a circuit-breaker. A rod 46, depending from the frame 80 47, has attached to it two arms 48 of dielectric material, which extend into the commutator and provide supports for two systems of brushes 49 49^a. The brushes 49 just touch the inner surface of rings 40, and they snap 85 across the slots 44, thereby breaking any circuit through them and the ring. Said brushes 49 are connected in parallel. The brushes 49^a bear against the inner surface of the rings 40 throughout a considerable portion of their 90 length, and thereby bridge the slot 44 and do not break any circuit passing through them and the ring. These brushes are connected in parallel to the ground.

A brush 50, rising from the cross-bar 51, 95 Fig. 5, extends up into the path of the lugs 45 on the commutator-rings 40, so as to make and break a circuit passing through them. The cross-bar 51 is mounted to slide in the guideway 22, and is connected by rods 52 to the 100 ribs 21 of the type-carriage. By this construction the cam-wheel moves the type-plate and the brush 50 simultaneously in the same direction.

As thus far described, it will be noted that 105 the type-plate is permitted to have four motions—viz., a longitudinally-sliding movement on the guides 22 and a transverse or to-and-fro oscillation on the shaft 27. The longitudinal movement is imparted by the cam-wheel, and said movement brings the particular type to its position to be printed, while the to-and-fro movement is accomplished by the switch-keys 6, and this movement brings that one of the four lines of type which is 110 controlled by the particular switch-key used into position for impression.

Referring now to Fig. 4, the type-hammer or printing-lever 53 is secured to the end of a plate 54, pivoted on a rod 55, suspended from 115 the upright bars 56, the upper ends of said bars 56 being secured to a plate 57, attached to the printing-magnet 58. On the outer end of the plate 54 a contact-plate 59 is secured and disposed within the field of the magnet 120 58. A spring 60 sustains the weight of the printing-lever 53 when the plate 59 is not attracted by the magnet 58, and a rod 61, provided with a contact-point 62, serves as a stop to limit the motion of the printing-lever 53 125 and also to make electrical connection between the head 61^a and the bar 54. The circuit of the spacing-magnets 93 is completed 130 through this rod 61, one wire being attached

to the head 61^a and the other wire to the bar 54. The electric circuit controlling the printing-magnet 58 is completed through the lower commutator-brush 50. When the coil 58 is energized, the contact-piece 59 is attracted and the hammer 53 strikes the type which happens to be immediately under it. Since the printing mechanism is stationary, it is obvious that the type must each in turn be brought into the same position under the hammer for printing. It will be noticed that there are a number of vacancies in the type-plate. Therefore the keys corresponding to these may be used for spacing between words.

15 The paper-roller 63 is of tubular form and may be of wood covered with india-rubber or similar material. Hubs 64 65 are secured to the opposite ends of the roller, the hub 64 having secured to its outer end a bevel-gear 66, the teeth of which mesh with those of a pinion 67, having a hand-wheel 68, provided with a dial on its uppersurface secured thereto. This dial is used in setting the paper-roller, and by means of it the paper-rolls on 20 the transmitter and receiver can be set at the same point, so that the lines and pages on the two copies of the despatch will correspond and the possibility of one running out before the other avoided. The pinion and milled 25 wheel are loosely mounted upon an upright shaft 69, having a central collar 70, which surrounds the hub 64. The opposite end of shaft 69 is attached to a rod 71, fixed to the frame of the instrument. A worm-shaft 72 passes loosely through the hub 64 and is engaged with the hub 65. The worm-shaft is mounted at its ends in the framework of the instrument, and a brake or screw lever 73 may be turned to hold said shaft in place or to permit it to be removed with the paper-roller. 30 Both ends of this shaft are adjustable vertically by means of the construction shown at one end in Fig. 15, in which 74 is the adjustable bearing-block for the shaft end and 75 is an eccentric disk, which may be turned by the thumb-screw 76 to bear upon the lower end of the pin 77 to raise or lower the shaft 72. This adjustment is rendered necessary to compensate for the thickness of paper as 35 it is printed and removed from the roller 63. The hub 65 is interiorly screw-threaded to fit the threads of the worm-shaft 72. The outer surface of the hub 65 is grooved at 78 for a wheel 79 of the paper-feed mechanism, to be 40 hereinafter described. At the opposite ends of the roller 63 spring-clamps 85 are provided for supporting an ink-ribbon 89. These clamps consist of semicircular members having their ends 86 bent outward, said ends being held together by the screws 87. Spiral 45 springs 88 surround said screws to separate the ends 86 when the screws are loosened. The rod 71 is clamped between the ends 86 below the roller to prevent the clamps from 50 turning with said roller. The ink-ribbon 89 is held at its ends by the screws 87 at the top of the roller, said ink-ribbon having clamp-

plates 30 at its ends, which engage the screws 87, as shown in Fig. 5.

I may use paper made up in a strip comprising a number of sheets or pages of letter-paper size, said strip being perforated at the side edges of each page, so that as a page is printed it may be detached and another is ready for the printing. The paper is applied to the paper-roller lengthwise the roller and lengthwise the page—that is to say, the diameter of the roller is approximately equal in measurement to the width of each letter-page—and the paper is placed upon the roller lengthwise. The type are also arranged lengthwise the roller and, owing to the spiral movement of said roller, an entire page is printed without the necessity of any shift of the carriage. The dotted lines at the left-hand side of Fig. 5 represent the spiral course taken by the printed lines, and it will be understood that the pitch of the threads of the worm-shaft 72 determines the space between the lines of print, owing to the fact that one revolution of the paper-roller moves the paper to the left just the distance of the space between two lines. If it is desired to use separate sheets of paper to print upon, provision is made for holding such paper on the roller.

In Figs. 4 and 11 are illustrated four rollers 91, journaled at their ends in bearings 92, extending from the clamps 85. These rollers may be composed of a central rod covered with rubber, and the rubber surfaces of the rollers bear with sufficient friction on the paper-roller to hold the separate sheets in place.

Referring now to Fig. 12^a, which illustrates the paper-feeding mechanism, the numeral 105 81 designates a semicircular dog rigidly keyed to a rod 83, pivoted on a rod 81^a at one end and carrying a pawl or detent 82 at its opposite end. A wheel 79, journaled upon the rod 81^a, shown broken away in said figure, runs in a groove 78 in the hub 65 of the paper-roller. The ratchet-wheel 84 is attached to the outer face of the hub 65, and the pawl or detent 82 engages the teeth of said ratchet-wheel to move the paper-roller step by step 110 as each letter is printed, each tooth of the ratchet-wheel corresponding to the space occupied by each letter. A rod 83 is connected at one end to the dog 81, and its opposite end carries an armature 83^a, placed within the field of the magnets 93. A supporting-spring 81^b is secured at one end to the rod 83, and its opposite end is attached to a support 80. This spring normally holds the armature out of contact with the magnets 93 and returns 115 the pawl or detent 82 to the next succeeding tooth of the ratchet 84 after each release of the armature 83^a by the magnets 93. The rod 81^a extends from the guide-wheel 79 to the support 80, and a guide-rod 27^a rests in 120 a yoke on the support 80 and is supported by the pendent bars 27^b and 27^c, Fig. 1. The lower end of the support 80 is interiorly 125 screw-threaded and fits the axle 72, Fig. 12.

The magnets 93 are rigidly secured to the support 80, being shown broken away for convenience of illustration. It will be understood that the magnets and their related mechanism travel longitudinally with the paper-roller, but do not rotate with it, as there is no positive connection between the support 80 and the hub 65. The circuit through magnet-coils 93 is only broken by the printing of a letter. The spacing action is thus completed before the next letter is printed.

The main shaft 27 is driven by the electric impulse-motor 33. This motor is provided with a very sensitive governor of modern construction and is synchronized with the motor at the opposite end of the line, as will be hereinafter described. Keyed to the end of main shaft 27 is a small pinion 97^a, the cogs of which mesh with those of a larger pinion 97^b, which is keyed on a stub-shaft journaled in the main upright of the frame of the machine. The wheel 97^b carries secured to its outer rim and insulated therefrom a metallic arm 97, which serves as a circuit maker and breaker. This arm 97 in revolving passes between and comes in contact with two downwardly-projecting metallic tongues 97^c, which are mounted on a horizontal bar of the frame and insulated therefrom. These tongues are included in the synchronizing-circuit to be hereinafter fully described. The magnets 95^a are secured to the frame and are included in the synchronizing-circuit. A bracket 95^b, Fig. 1, is attached to the motor-frame and supports an indicator-dial 95. This dial is provided with a hand 95^c, which is keyed to a horizontal arm 95^d, whose outer end is pivoted to the upwardly-extending rod 95^e, said rod carrying an armature 95^f, rigidly secured to its upper end. When the circuit is completed through coils 95^a, the armature 95^f will be attracted, which will in turn actuate the hand 95^c and give a visible indication that the synchronism is in harmony. A switch S' is incorporated in the synchronizing-circuit, as shown in the diagrammatic view. A graduated dial 97^d, of ordinary construction, supplied with an indicator-hand 97^e, is secured to the upright of the frame immediately behind the small pinion 97^a. This dial is used in adjusting the synchronism.

The different circuits controlling both the transmitting and receiving machines and their various mechanisms, together with the circuits connecting the two machines, will now be described in detail. It is to be understood that this wiring of the machine in the most part is only provisional.

For convenience the following system has been adopted for designating the circuits. Reference should be made to the diagrammatic views:

C' is the holding-circuit on the transmitter.

C² is the printing-circuit, which includes both the transmitter and receiver.

C⁴ is the spacing-circuit common to both machines.

C⁵ is the motor-circuit common to both machines.

C⁶ is the bell-circuit, which includes both machines.

C⁷ is the synchronizing-circuit, including both machines.

C⁸ is the circuit pertaining to shift-key No. 2.

C⁹ is the circuit pertaining to shift-key No. 1. 75

C¹⁰ is the circuit pertaining to the shift-key No. 3.

C¹¹ is the circuit pertaining to the shift-key No. 4.

The following additional mechanism must be provided in order that my machine may be adapted to be used as a receiver: Connected by wires to the back connections of the switch-keys 6 are points or binding-posts a b c d, as shown in diagram. A second series 85 of points or posts a' b' c' d' are supplied with electrical connections to be hereinafter traced. Four metallic strips A B C D are each pivoted at one of their ends to points e f g h, which points are connected to the main-line wires. 90 When the machine is used as a transmitter, strips A B C D are placed in contact with points a, b, c, and d, and when it is used as a receiver they are placed in contact with the points a', b', c', and d'. In order that these 95 strips may be shifted in unison in making the change transmitter to receiver, a strip E of dielectric material is secured to each of the strips. A ground G' is cut in on the receiver and cut out on the transmitter by 100 means of a plug P'. The upper contacts of the two middle keys are bifurcated, as previously described, and are connected to ground. Plugs P² and P³ are provided. These plugs are inserted on the transmitter and are taken 105 out on the receiver, thus breaking the connection. With the exception of these minor changes the two machines are identical. The shift-magnets 30 are shown in the diagram and are distinguished from each other by the 110 symbols 30' 30² 30³ 30⁴.

It will be understood that each of the printing-keys 5 is connected to one of the brushes 49, which brush is insulated from all the other brushes 49, since the commutator-rings are insulated from one another. The circuit through any one of the brushes 49 is completed to the ground through the corresponding brush 49^a, which brushes are connected in parallel to the ground. The only batteries in the main 120 line are the batteries B', and but one of these is employed at any one time, as the one on the receiver is always cut out.

Circuit C', Fig. 16, starts from battery B', which is grounded, and proceeds through the 125 key-magnets of one of the printing-keys 5, through contact-point 12^a, through key, (when key is down,) through brush 49, through commutator-ring 42, through upper brush 49^a, (this brush bridges the slit 44 of the ring and can never break a circuit made through it,) and to ground. This circuit is established whenever a printing-key is depressed. It then persists until the lower brush 49 crosses

the cut 44 and breaks the circuit, thereby releasing the key. The upper brush 49 bridges the slit 44 and cannot break the circuit. During the time this circuit exists the letter is 5 printed by the printing-circuit C², which is completed by means of brush 50. This circuit can be one of high resistance, so as not to rob the main line.

Circuit C² is the same as circuit C' up to 10 and including the brush 49. From thence it continues through the commutator ring and lug to the lower brush 50, through the printing-magnets on the transmitter, through the main line, through the printing-magnets on 15 the receiver, through the brush 50, through the lug and ring to the corresponding upper brush 49^a, and thence to ground. This circuit is only brought into existence after one of the printing-keys has been depressed and 20 the brushes 50 simultaneously contact with the lugs on the corresponding ring of the commutator. It is broken as soon as one of the brushes 50 passes from off the lug. It is obvious that this circuit can only be completed when the two machines are in accord—that is, synchronized.

Circuit C⁴ starts from local battery B³, thence through binding-post, through spacing-magnet coils, through printing-lever, 30 through lower contact, through upper contact, through pendant, through wire back to binding-post, and back to battery B³. This circuit is used for spacing and is always closed except during the actual printing of a letter. 35 When the printing-lever is drawn down, the circuit is broken, the armature on the spacing-magnet is released, and the pawl is set. When the circuit is closed again, the armature is attracted and the pawl engages the 40 ratchet-wheel and the cylinder rotated one space.

Circuit C⁵, controlling the motor, starts from a source of electricity S and proceeds through the motor, through a switch, and thence back 45 to the source of electricity. In practice I may connect this circuit with a relay on the quadruplex, in order that the motor may be started by the operator at the opposite end.

Circuit C⁶ starts from battery B⁴, which is 50 grounded, thence through bell-magnet coils, thence through switch, through main line to receiver, through switch, through bell-magnet coils, through battery B⁴, through binding-post to ground. This circuit is used for 55 signals and may be operated as a local circuit connected to a relay.

Circuit C⁷ for beating and adjusting the synchronism starts from ground and proceeds through battery B⁵, thence through magnet- 60 coils on the sounder, through tongue 97^c on circuit-maker, through point 97, through second tongue 97^c, through main line to the receiver, through tongue 97^c on circuit-maker, through point 97, through second tongue 97^c, 65 through magnet-coils on the sounder, thence through battery B⁵ to ground. This circuit is always broken except when the circuit-

breakers 97 are running in unison. This is the case when the synchronism is perfect. In adjusting the machine these breakers are each 70 set to conform with the same straight portion of the cam-wheel. This is readily accomplished by the dial arrangement in connection with the pointer on 97^a. In order to bring these breakers into accord after the machines 7 have both been started, it is only necessary to apply friction to the main shaft 27 on one of the machines, thus retarding the motor.

The switches S', with their connections, are provided for testing the synchronism. By 80 closing one of them the sounder will beat whenever the opposite breaker passes between the tongues 97^c.

For operating the shifting mechanism there are four circuits C⁸, C⁹, C¹⁰, and C¹¹. The circuits C⁸ and C¹⁰ control the lower shift-magnets, which bring the middle lines of type into position. When the outer line is required—say line beginning with X—the circuit controlling the line H is first closed and then the 90 circuit controlling the line X would be closed. This is necessary because the magnets will not throw far enough to shift line X into position directly. The depressing of the remaining middle key will break the circuits 95 controlled by the two keys.

Circuit C⁸ starts from ground connection G² on top contact of key 3. It proceeds through top contact of key 3, the key being up the upper contact is closed by the point 100 6^a, thence through key-magnets key 2, key being depressed it is then held down, then through shift-magnets 30', then through bottom contact-key 2, then through key 2, key 2 being down, then through back connection 105 key 2 and strap B; then through line-wire to receiver, then through strap B, then through key-magnets key 2, holding key down, then through shift-magnets 30', then through bottom contact-key 2, and then to ground G'. It 110 will be noted that this circuit is completed by depressing key 2 on the transmitter when plugs P² and P³ are in on the transmitter and out on the receiver and plug P' being in on the receiver and out on the transmitter. This circuit 115 is broken by depressing key 3.

Circuit C⁹, which is always used by adding it to C⁸, starts from bottom contact-key 2 on the transmitter, this key being down, thence through key-magnets key 1, thence through 120 shift-magnets 30^b, thence through bottom contact-key 1, this key being down, thence through key 1, through back connection of key 1 and through strap A to line-wire to receiver; thence through strap A, then through 125 lower contact-key 1, thence through shift-magnets 30^b, thence through key-magnets key 1, holding down key 1, thence through bottom contact-key 2 to ground G. This circuit is always broken when C⁸ is broken and is 130 only used by being added to it.

Circuit C¹⁰ starts from ground G³ and proceeds through top contact-key 2 on the transmitter, key being up, thence through key-

magnets key 3, (this key being down it is held,) thence through shift-magnets 30², thence through bottom contact-key 3, key being down, thence through back key 3, thence 5 through back connection key 3 to strap C, and over line-wire to receiver; then through key-magnets key 3, then through shift-magnets 30², then through bottom contact-key 3, and to ground G'. This circuit is similar to 10 circuit C⁸.

Circuit C¹¹ starts from bottom contact-key 3 on the transmitter, this key being depressed, thence through key-magnets key 4, thence through 15 shift-magnets 30⁴, thence through bottom contact-key 4, key being depressed, then through key 4, thence through back connection of key 4, and through strap D to line-wire to receiver; then through strap D to lower 20 contact-key 4, then through shift-magnets 30⁴, then through key-magnets of key 4, then through lower contact-key 3 to ground G'. This circuit is similar to C⁹ and is only used when added to circuit C¹⁰.

The operation of my machine may be briefly 25 summarized as follows: We will suppose that the two machines are connected up as described and that the back connections of the shift-keys on the transmitter are connected to straps A B C D and the ground is cut 30 out on the transmitter by removing plug P' and the top contacts of keys 2 and 3 are grounded by inserting plugs P² and P³, Fig. 17. The signal is then given by means of the bell-circuit and the operators of both machines start their machines and adjust their 35 synchronism by means of the synchronizing-circuit, friction being applied by hand to the main shaft to get the machines to accord. The paper-roller is filled with paper and run 40 up to the extreme end by throwing on cross-belt 100. The operator will now start sending. We will suppose he wishes to send the letter A. He would press shift-key No. 2, completing circuit C¹⁰, which would throw 45 the horizontal line containing A to its proper position for printing. The key would remain locked down by the action of its key-magnets. The printing-key controlling A would now be struck. It would close circuit C' and 50 be locked down until the lug 45 on the commutator-ring came around and touched the guide-brush 50 and printed the letter on each machine by means of the circuit C². This circuit is immediately broken by the passing 55 on of the lug, and the brush 49 releases the key by breaking circuits C' on passing slit 44. The printing of the letter breaks circuit C⁴, and thus permits the pawl 82 to take a new grip. When this circuit is again completed, the magnets 93 attract the armature 60 and space for the next letter to be printed. Suppose the next letter is N. The operator would strike shift-key 2, which would simultaneously release key 3 and lock itself, and 65 the letter would be printed by striking the printing-key corresponding to N. If a space was now required, key 1 would be struck and

the line "X" brought into position. Any one of the keys corresponding to the four blanks could now be struck and a space would be 70 made by breaking and making circuit C⁴, but no letter would be printed.

I claim—

1. In a printing-telegraph instrument, a type-plate, means for imparting four motions 75 to said plate, keys for printing the types, keys for shifting the plate, and means for automatically locking the shifting-keys until another shift-key is actuated, substantially as described.

2. In a printing-telegraph instrument, a grooved cam-wheel, a type-plate carrying a set of types, a traveler connected to the type-plate and running in the grooves, means for rapidly revolving the cam-wheel to reciprocate the type-plate, means for moving the type-plate transversely to the reciprocation, 85 a set of keys for actuating the types, substantially as described.

3. In a printing-telegraph instrument, a 90 type-plate carrying a set of types, a cam-wheel for reciprocating said type-plate, a set of commutator-rings, a brush in contact therewith, a type-lever for giving impression to the type, and electrical means for actuating 95 said parts, substantially as described.

4. In a printing-telegraph instrument, a grooved cam-roller, a type-plate actuated by 100 said roller, a frame within which the type-plate slides, a commutator comprising a series of rings, a brush connected to the type-plate and moved simultaneously therewith, and means for swinging the frame transversely to present different lines of type to the printing-point, substantially as described. 105

5. In a printing-telegraph instrument, a set 110 of types mounted in a plate having guide-ribs thereon, a grooved frame in which the ribs are adapted to slide, a cam-wheel for moving the type-plate longitudinally, said frame being suspended from a shaft, and an electromagnet for rocking said frame when a shift-key is actuated, a set of shift-keys, and a set of type-keys, substantially as described.

6. In a printing-telegraph instrument, a 115 commutator comprising a series of metallic rings and interposed rubber rings, said rings having disconnected ends, brushes inside the rings and in contact therewith, a brush bearing on the outside of said rings, and means 120 for shifting the outer brush, substantially as described.

7. A commutator consisting of a series of metallic rings insulated from one another, each of said rings having a transverse slot or 125 cut therein, one or more projections or lugs on the periphery of each of said rings, means for maintaining a traveling contact with said rings which bridges said cuts, means for maintaining a traveling contact with said rings 130 which is interrupted by its passage over said slots or cuts, and means for making and breaking a circuit through said lugs, substantially as described.

8. A shifting mechanism comprising a pivoted arm attached to a type-bearing plate, said type-bearing-plate, armatures mounted on said arm and extending across the poles of electromagnets, electromagnets mounted adjacent to said armatures and adapted to actuate said arm and hold it in four independent positions, substantially as described.
9. A synchronizing system comprising an electric circuit, circuit-breakers one on the transmitter and one on the receiver, said circuit-breakers being connected to their respective instruments in such a way that the circuit is completed and broken by said circuit-breakers simultaneously at both stations, a switch for cutting out one of said circuit-breakers, and sounders included in said circuit and adjacent to said circuit-breakers, substantially as described.
10. In combination with a type-plate and a set of types mounted thereon, of a wheel having a groove therein which extends four times around its circumference and consists of alternate parallel and diagonal portions, constructed to reciprocate said type-plate longitudinally by turning on its axis in one direction, means for connecting said type-plate and said grooved wheel, to enable the plate to be reciprocated thereby, and means for printing said type.
11. In combination with a set of type mounted in a type-plate, of the grooved wheel constructed to intermittently actuate said type-plate to reciprocate it, by revolving on its axis in one direction and means for connecting said type-plate and said grooved wheel to enable the type-plate to be reciprocated thereby.
12. In combination with a set of type mounted in a type-plate, of the grooved wheel constructed to reciprocate said type-plate longitudinally by being revolved on its axis in one direction and means for connecting said type-plate and said grooved wheel to enable the plate to be reciprocated thereby.
13. In combination with a set of type mounted on a type-plate, of the grooved wheel constructed to reciprocate said type-plate longitudinally by revolving on its axis in one direction, means for connecting said type-plate and said grooved wheel to enable the plate to be reciprocated thereby, means for moving said type-plate transversely, and means for printing said type.
14. In combination with a set of type mounted in a type-plate and means for reciprocating said plate, of the brush adapted to be reciprocated in unison with said type-plate, the mechanism for printing said type, and means for completing a circuit through said brush to actuate said printing mechanism.
15. In combination with a paper-bearing or platen roll mounted on a worm-shaft, of the ratchet-wheel secured to said roll, the dog adapted to engage said ratchet to actuate said roll, the armature, means for connecting said dog and said armature, means for holding said armature out of contact with the mag-

nets when they are not attracting it, the magnets mounted in coils and adapted to attract said armature, and means for making and breaking a circuit through said magnet-coils to intermittently turn the platen-roll.

16. In combination with a paper-bearing roller supported on a worm-shaft and means for revolving said roller, of the clamps encircling said roller, near the ends, and adapted to support a type-ribbon, means for holding said clamps from turning with said roller, and the type-ribbon supported on said clamps.

17. In combination with a set of types mounted on a type-plate and means for actuating said type-plate, of the pivoted bar provided with a printing-hammer and an armature mounted thereon, the stop for limiting the upward movement of said bar, the spring adapted to hold said pivoted bar normally in contact with said stop, the magnets mounted in coils and positioned to attract said armature, when energized, to actuate said hammer to strike and print one of said types, and means for energizing said coils to energize said magnets.

18. In a printing-telegraph instrument, a type-plate carrying a set of type, a grooved cam-wheel adapted to be revolved on its axis to reciprocate said type-plate, a traveler on said type-plate adapted to run in the groove in said cam-wheel, and means for printing said type.

19. In a printing-telegraph instrument, a type-plate provided with a set of type, means for actuating said type-plate, means for printing the type, said means being controlled by type-keys, means for rocking the plate which is controlled by shift-keys, means for locking each of said shift-keys after it has been depressed, and means for releasing the locked shift-keys, which is operated by one of the other shift-keys.

20. In a printing-telegraph, a commutator comprising a series of metallic rings and interposed dielectric rings, said metallic rings having disconnected ends and lugs thereon, brushes mounted inside said rings and adapted to contact therewith, a brush adapted to contact with said lugs to make and break a circuit, and means for actuating said rings.

21. In combination with the guide-frame having guide-grooves therein, of the type-plate bearing a set of type, the segments secured to said type-plate and provided with guide-ribs adapted to slide in said guide-grooves, the traveler-support comprising the top plate bearing a traveler and the segments secured to said top plate and adapted to fit the segments on said type-plate, and means for actuating the traveler to reciprocate said type-plate in said grooves.

In testimony whereof I have hereunto set my hand in presence of two subscribing witnesses.

EDGAR KINSMAN.
